TEXTILE TRUCK FOR YARN HOLDERS

James M. Jones, Charlotte, N. C.

Application June 11, 1942, Serial No. 446,637

4 Claims. (Cl. 220—93)

This invention relates to textile bobbin trucks and more especially to an article of this type having a novel means for elevating the contents to an accessible position near the upper open side thereof.

It is a well known fact in textile circles that machines such as spinning frames, fly frames, slubbers and the like are equipped with numerous spindles upon which bobbins or yarn holders are adapted to removably fit. After the machines have been operated for some time, these yarn holders become filled, at which time the machine is stopped so as to doff or remove the filled holders from the spindles and to replace empty holders instead. In order to quickly carry out this operation a double compartment wheeled truck is usually employed, one compartment being adapted to receive the filled holders and the other compartment carrying a supply of empty holders to be used for replacement as the filled holders are removed. As the supply of empty holders is used it is necessary for the doffing operator to stoop lower to reach the holders. This condition slows up the doffing operation and also tires the doffing operator.

It is an object of this invention to provide an improved textile truck in which the compartment containing the empty holders is provided with a hand-operated adjustable bottom capable of supporting the holders at any desired level within the compartment.

Specifically the structure comprises a container having a pawl and rack mechanism disposed along opposite side walls whereby the adjustable bottom and the supported holders may be easily elevated to the desired position.

It is another object of this invention to provide a bobbin truck of the class described comprising a plurality of telescopically mounted containers mounted in the empty holder compartment, together with pawl and rack mechanism for elevating said containers. By providing a plurality of telescopic containers the holders may be kept out of contact with the compartment side walls while being elevated, and therefore binding and chafing will be prevented.

Some of the objects of the invention having been stated, other objects will appear as the description proceeds when taken in connection with accompanying drawings in which:

Figure 1 is an isometric view of my improved bobbin or yarn holder truck;

Figure 2 is a longitudinal sectional view taken along the line 2—2 in Figure 1;

Figure 3 is an isometric view of a portion of the

false bottom which slidably fits within one of the truck compartments;

Figure 4 is a sectional plan view taken along the line 4—4 in Figure 2;

5 Figure 5 is a longitudinal vertical sectional view similar to the right-hand portion of Figure 2, but illustrating a slightly modified form of the invention;

Figure 6 is an isometric view of the telescopic 10 container assembly adapted to operate in the empty yarn holder compartment of the modified form of the invention shown in Figure 5;

Figure 7 is the view similar to Figure 5, but 15 showing the telescopic container assembly in elevated and contracted position;

Figure 8 is the sectional detail view similar to 20 the upper central portion of Figure 5, illustrating the pawl and rack mechanism for holding the upper member of the container assembly in elevated position.

Referring more particularly to the drawings the numeral 10 denotes a supporting framework which, in turn, is supported by center wheels 11 and end wheels 12. This truck has mounted on

25 the upper side thereof boxes 14 and 15, the box 14 being adapted to contain empty yarn holders and the box 15 being adapted to receive filled 30 yarn holders. In the use of the present invention the truck assembly is rolled down an aisle between textile machinery such as spinning frames, draw frames, fly frames, and the like

35 while the operator removes the filled bobbins of yarn from the spindles and places them in box 15. Almost simultaneously the operator removes the empty bobbins from box 14 and places them upon the spindles previously occupied by the filled 40 bobbins. As heretofore stated it is necessary for the operator to gradually stoop lower as the yarn holders are used from box 14. The present invention contemplates the use of a hand-operated false bottom which may be elevated to a plurality of different positions thereby causing the top of the mass of yarn holders to be disposed within 45 easy reach without unnecessary stooping.

45 The box 14 has suitable vertically disposed slots 16 in two of its opposed side walls. These slots slidably receive extensions 17 which are employed as handles and which are an integral part of a supporting member such as a channel 18. Upon

50 this channel a suitable plate 19 is secured by any suitable means such as screws 20. By observing Figures 2 and 4, it will be seen that the edges of this plate are disposed in close proximity to the four side walls of box 14, thereby forming a false 55 bottom.

In order to provide means for holding the plate 19 in a plurality of elevated positions within the box 14, suitable racks 22 are provided on each side of each vertically disposed slot 16. These racks have spaced notches 22a therein, in which the end of one leg of an L-shaped pawl 23 is adapted to yieldingly fit. A pawl 23 is pivotally secured to each end of the channel supporting member 18 as at 24 so that the horizontal legs thereof will normally be disposed in spaced relation to extensions 17. As a means for yieldingly urging the vertical legs of pawls 23 toward each other and into engagement with the rack members 23 a tension spring 25 is employed, said tension spring having its ends connected to the vertical legs of the pawls 23. The spring 23 is disposed directly beneath the supporting member 18 and penetrates both of the slots 16.

Since longer sides of the truck should be kept free from projections the extensions 17 and channel member 18 have been placed longitudinally of the truck so that one of the extensions 17 will be located on the truck end. On account of the proximate side walls of boxes 14 and 15 being disposed so close together it has been necessary to cut an additional vertical slot 28 in box 15 to permit the other extension 17 to project to an accessible position within box 15. When it is desired to elevate the yarn holders within the box 14, the operator engages both handle members 17 simultaneously, and then pulls the channel member 18 and the associated plate 19 upwardly until the lower ends of pawls 23 engage the desired notches 22a in the racks 22. If it is desired to lower the plate member 19 the horizontal legs of pawls 23 are engaged and rotated upwardly to cause the vertical legs of the pawls to become disengaged from the notches 22a. With the pawls in a disengaged position the false bottom can be easily lowered the desired amount.

Figures 5 to 8 inclusive show a slightly modified form of the invention. In this form the truck 10 has a box 30 mounted thereon, said box having a compartment 31 for empty yarn holders and a compartment 32 for filled yarn holders. These compartments are separated by a single wall or partition 33. Each of two opposed walls of compartment 31 have a vertically disposed slot 34 therein in which suitable tube supporting handles 36 and lower container supporting handles 56 are mounted for vertical sliding movement. The handles 36 and 56 are secured to the opposed sides of tubular member 39 and container member 40 respectively.

It can be seen that the lower rim of tubular member 39 has an in-turned flange 39a which fits beneath an out-turned flange or rim 40a of container member 40. These flanges serve as a tie between members 39 and 40 so that when member 39 is elevated from the position shown in Figure 5 the container 40 will also be elevated. The container 40, however, is telescopically mounted in the tubular member 39, and the tubular member 39, in-turn, is slidably mounted in the compartment 31 of box 30.

The tubular member 39 is held in elevated position very much in the same manner as the plate 19 is held in the preceding form of the invention. A rack 41 is disposed on each side of each slot 34 and this rack has a plurality of spaced notches 41a therein. The handle 36 serves as a supporting means for L-shaped pawls 42, one leg of each pawl yieldingly engaging the notches in the racks. The pawls 42 are pivotally secured as at 43 to handle members 36. A compression

spring 47 serves to normally urge one leg of the pawl into engagement with racks 41 and notches 41a. This spring encircles a pin 48, which pin penetrates a slot 49 in the vertical leg of pawl 42. Pin 48 has one end threadably secured in handle 36 and also has a head 48a for confining spring 47 around the pin. (See Figure 8.)

The lower container 40 is individually supported in an elevated position by a similar means. This means comprises an L-shaped pawl 54 which is pivotally secured as at 55 to the handle 56. A tension spring 57 normally urges one leg of the pawl into engagement with rack members 42.

Let us assume that the container 40 and the tubular member 39 in Figure 5 are filled with empty yarn holders, thereby leaving empty that portion of compartment 31 which is above tubular member 39. In order for the operator to remove yarn holders when in this position, it will be necessary for him to reach at least to the top of tubular member 39. If the operator so desires, he may grasp the handles 36 and then elevate the tubular member until its upper edge is substantially at the same elevation as the top of compartment 31.

This elevation of the tubular member will also elevate the yarn holders thereby making them more accessible. Since inter-engaging flanges 39a and 40a are provided the container 40 will also be elevated to substantially the same position previously occupied by tubular member 39. With the members 39 and 40 in elevated position the operator will use the empty bobbins from the member 39 until the top of container 40 is reached. At this time he will grasp handles 56 and raise container 40 to a position approximately the same height as of the top of compartment 31, that is, to a position such as shown in Figure 7. By providing a telescopic assembly as shown, the empty bobbins or yarn holders are never caused to slide against the side wall of the compartment 31 while being elevated.

With certain types of yarn holders some difficulty is encountered on account of binding when a false bottom such as shown in Figures 1 to 4 inclusive is employed, because a bobbin or yarn holder will simultaneously engage the side wall of the compartment and the false bottom while the bottom is being elevated. It has been found, however, that this binding is somewhat eliminated if precision work is employed when making the container. The modified form of the invention completely eliminates this binding but is not capable of maintaining the top level of the empty 55 yarn holders as near as the top of the compartment at all times as in the first form of the invention.

In the drawings and specification, there has been set forth a preferred embodiment of the 60 invention, and although specific terms are employed, they are used in a generic and descriptive sense only and not for purposes of limitation, the scope of the invention being defined in the claims.

65 I claim:

1. The combination in a box for empty yarn holders of a vertically slidable false bottom, said box having a vertically disposed slot in two opposite sidewalls, projections extending from opposite sides of said bottom through said slots to the exterior of the box, vertically disposed racks secured to the exterior of said box adjacent said slots, and a pair of pawls carried by said projections and engageable with said racks whereby the

bottom may be held in a plurality of elevated positions.

2. The combination in a box for empty yarn holders of a vertically slideable false bottom, said box having a vertically disposed slot in two of its sidewalls, a projection extending from said bottom through each of said slots to the exterior of the box, vertical rack on the exterior of the box and disposed adjacent each of said slots, and pawls carried by said projections and engageable with said racks whereby the bottom may be held in a plurality of elevated positions.

3. The combination in a box for empty yarn holders of a vertically slideable container within said box, the side walls of said container being disposed in close proximity to the side walls of the box and the depth of said container being less than the depth of the box, a vertically slideable tubular member in said box, said tubular member being telescopically mounted over said container, inter-engaging means between said tubular member and said container, said box having a verti-

cally disposed slot in each of opposed sidewalls, a projection on opposed sides of both the container and tubular member and extending through the slots, a rack on the exterior of opposed sides of the box and disposed adjacent each of said slots, a pawl carried by each projection and adapted to engage the rack to hold the container and tubular member in elevated position within the box.

4. A container having a pair of vertically disposed slots in two opposite sidewalls, a supporting member disposed within the container and forming a false bottom member and being vertically slideable within the container, a pair of projections mounted on the supporting member and projecting through said slots, a vertically disposed rack disposed adjacent each of said slots, a spring-pressed pawl pivoted on each projection and adapted to engage the rack to hold the supporting member in elevated adjusted position within the container.

JAMES M. JONES.
